US0D1087217S

(12) **United States Design Patent** (10) **Patent No.:** **US D1,087,217 S**
(45) **Date of Patent:** **** Aug. 5, 2025**

(54) **ELECTROSTATIC ADSORPTION TOOL FOR CUTTING PLOTTER**

(71) Applicant: **Silhouette Japan Corporation**, Kanagawa (JP)

(72) Inventor: **Mayumi Sato**, Yokohama (JP)

(73) Assignee: **Silhouette Japan Corporation**, Kanagawa (JP)

(**) Term: **15 Years**

(21) Appl. No.: **29/930,216**

(22) Filed: **Feb. 28, 2024**

(30) **Foreign Application Priority Data**

Sep. 4, 2023 (JP) ..... 2023-017971 D

(57) **CLAIM**

The ornamental design for an electrostatic adsorption tool for cutting plotter as shown and described.

DESCRIPTION

FIG. 1 is a front perspective view of an electrostatic adsorption tool for cutting plotter showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a top view thereof;

FIG. 7 is a bottom view thereof;

FIG. 8 is a left side view thereof; and,

FIG. 9 is a right side view thereof.

1 Claim, 9 Drawing Sheets
